(57) **CLAIM**

The ornamental design for a engine hood of tractor, as shown and described.

DESCRIPTION

FIG. 1 is a right side view of a engine hood of tractor, wherein the tractor as shown is only environmental structure and does not form part of the design of the invention; FIG. 2 is a left side view thereof, wherein the tractor as shown is environmental structure and does not form part of the design of the invention;

FIG. 3 is a front side view thereof, wherein the tractor as shown is environmental structure and does not form part of the design of the invention;

FIG. 4 is a top plan view thereof, wherein the tractor as shown is environmental structure and does not form part of the design of the invention;

FIG. 5 is a left side perspective view thereof; and,
FIG. 6 is a right side perspective view thereof.

The broken line showing is for illustrative purposes only and forms no part of the claimed design.
